UNLOADER FOR GAS COMPRESSORS

Albert E. Schneider, Carter Lake, Iowa, assignor
to Baker Ice Machine Co. Inc., Omaha, Nebr., a
corporation of Nebraska

Application February 11, 1932. Serial No. 592,270

8 Claims. (Cl. 230—24)

My invention relates to an unloader for gas compressors and more particularly to mechanism of that character for use in mechanical refrigeration apparatus operated by electrical motors having relatively low power consumption; the principal object of the invention being to utilize the current surge incidental to initial and intermittent starting of the motor for controlling operation of the compressor suction valves, thereby 5 effecting temporary relief of the compressor load on the motor.

In accomplishing this and other objects of the invention, I have provided improved details of structure, the preferred form of which is illustrated in the accompanying drawings, wherein:

Fig. 1 is a perspective view of a refrigerating apparatus equipped with my improved unloading mechanism, parts of the compressor walls being broken away to illustrate the location and operation 10 of the unloading mechanism.

Fig. 2 is a perspective view of the suction valves illustrating related parts of the unloading mechanism in spaced position, to better illustrate their construction.

Fig. 3 is a perspective view of one of the discharge valves and its cage.

Fig. 4 is an enlarged sectional perspective view of one of the suction valves.

Fig. 5 is a vertical section of the compressor 25 head through one of the compression cylinders.

Fig. 6 is an enlarged vertical section through one of the cylinders showing the suction valve and control parts in unloading position.

Fig. 7 is a similar view showing the parts as 30 they appear when the compressor is operating at normal speed.

Fig. 8 is a circuit diagram including the motor running and starting windings, the unloading coil and the automatic switch for effecting energization of the starting winding and the unloading coil.

Referring more in detail to the drawings:—

1 designates a refrigerating apparatus wherein the condenser coil 2, compressor 3 and its operating motor 4 are located relatively to each other to form an enclosed self-contained unit.

The compressor illustrated includes a cylinder housing 5 having its upper and lower ends closed by partition walls 6 and 7 to form a low pressure 50 chamber 8. Provided in the partition walls are pairs of aligning circular openings 9 and 10 forming seats for supporting upper and lower ends of cylinders 11.

The openings 9 and 10 are preferably located 55 close to a side wall of the housing to provide

space adjacent the opposite side wall to accommodate unloading mechanism installed through an elongated opening 12 provided in the partition 6, as later described. Each cylinder may comprise a sleeve 13 having a peripheral flange 14 for seating in a counter-bore 15 of the opening in the upper partition and having a reduced skirt portion 16 pressed into the opening in the lower partition. The cylinders are provided at a point below the upper partition with arcuate-shaped auxiliary ports 17 opening to the low pressure chamber, and with gas inlet channels 18 extending vertically from the upper faces of the flanges 14 to the ports 17, so that refrigerant may be drawn from the low pressure chamber through the channels 18 upon the suction stroke of the compressor pistons, as well as directly through the auxiliary ports when the pistons have reached the ends of their suction strokes, and whereby the refrigerant may be returned to the low pressure chamber upon actuation of the unloading mechanism, as later described.

Seated on the upper partition 6 is a valve plate 19 conforming to the shape of the cylinder housing and provided with a longitudinal opening 20 aligning with the opening 12 previously described, and with recesses 21 on its bottom face in line with the channels 18 to prevent the plate from closing off passage of refrigerant to and from said channels.

The discharge valve plate is also provided concentrically of each cylinder with a discharge port 22 communicating with a high compression chamber 23 provided in a cylinder head 24 that is mounted on the upper face of the valve plate. 90 To prevent leakage, suitable gaskets 25 are inserted between the cylinder housing and the lower face of the valve plate and between the upper face of the valve plate and the cylinder head. The head and plate are retained by suitable stud bolts 26, as in standard compressor construction.

The low compression chamber is provided with a gas inlet port 27 communicating with a suction line 28 that is connected to the refrigerant expansion coil (not shown), and the high pressure chamber is provided with a discharge port 29 communicating with a high pressure line 30 connected with the condenser coil 2.

The discharge ports 22 are valved by disk type valves 31 that are retained in seating relation with the upper face of the valve plate by a valve cage member 32 which preferably comprises a spring metal leaf 33 fixed to a boss 34 located on the plate at a point midway between the cylinders, a screw 35 being extended through an opening in 110

the leaf and threaded into the boss. The ends of the leaf extend over the discharge valves and are provided with a circular series of depending lugs 36 encircling the valve disks and having 5 their ends engaging the valve plate to form cages in which the valves are reciprocably retained under control of spring-like tongues 37 stamped from the metal leaf.

The auxiliary ports 17 are valved by the compressor pistons 38 and the upper ends of the channels 18 are valved by disk-shaped valves 39 seated in recesses 40 formed in the cylinder flanges 14 at the upper ends of the cylinders as best illustrated in Fig. 6.

15 The valves 39 are normally urged to their seats by a leaf spring 41 having its intermediate portion anchored in a groove 42 formed in the under face of the valve plate and extending longitudinally in line with the inlet valves. The free ends 20 43 of the spring are preferably bent downwardly to engage the upper face of the valves to retain them on their seats.

25 The motor 4, preferably of the split phase type, is directly connected to the operating shaft (not shown) of the compressor for actuating the pistons 38 whereby each piston on its suction stroke effects lifting of its related suction valve 39 to draw a charge through the channels 18 into the cylinder. When the piston has reached the 30 limit of its suction stroke, the auxiliary port 17 is uncovered to allow additional gas to enter the cylinder to assure the complete filling thereof. When the piston begins its compression stroke, the port 17 is closed thereby and the suction 35 valve is closed by the compression of the gas, supplemented by the pressure of the spring 41, so that the trapped gas is discharged through the port 22, lifting the valve 31 against tension of the tongues 37 and gas pressure in the high pressure 40 chamber.

45 In order that a compressor of the type illustrated may be actuated by a motor of the split phase type having relatively low current consumption, it is necessary to initially relieve the motor from the load of compression until the 50 motor attains its proper working speed. To effect this result I provide for automatically lifting the suction valves from their seats so that the gas is simply drawn into the cylinders and returned to the low pressure chamber until the motor has attained its proper working speed, as now described.

55 Reciprocably supported in the channels 18 are triangular-shaped pins 44 having their upper ends adapted to bear against the under face of the suction valves and their lower ends are supported on lever arms 45 projecting from a rock shaft 46.

60 The rock shaft 46 is pivotally mounted in the low pressure chamber and comprises a cylindrical rod 47 having reduced pivot ends 48 and 49 which are respectively supported in a socket 50 formed in a wall of the cylinder housing and in a socket 51 provided in the end of a screw 52 that 65 is threaded through the opposite wall of the housing as illustrated in Fig. 1. The shaft is thus supported in position so that the lever arms extend into the auxiliary ports 17 to lift the pins when the shaft is rocked on its pivots.

70 In order to effect operation of the rock shaft, it is provided intermediate the lever arms 45 with an oppositely directed lever arm 53 forming an armature of an electro-magnet 54 now described.

75 The electro-magnet 54 includes a spool 55 having a laminated core 56 supported on bracket

80 arms 57 that are attached to bosses 58 extending upwardly from the lower partition 7 of the cylinder housing, the brackets being secured to the bosses by suitable fastening devices 59. The brackets preferably extend upwardly within the spool along the sides of the core 56 and are bent outwardly to lie flat against the upper face of the spool as illustrated in Fig. 1, to retain the spool and form an abutment 60 for a leaf spring 61. The flat leaf spring 61 is attached to the rock shaft and extends parallel with the armature lever arm 53 to normally retain the lever arms 45 in retracted position, so that the lever arms 45 will allow the suction valves to seat and perform their normal function of trapping the refrigerant charges in the cylinders on the compression strokes of the pistons. In order to energize the electro-magnet, it is connected into the motor circuit as now described.

90 Referring to the circuit diagram illustrated in Fig. 8, 62 and 63 represent the lead wires of an electric circuit to which is connected the motor running winding 64 of the split phase motor. Also connected in the circuit in series with the motor running coil is a solenoid 65 for actuating 100 a switch 66 that connects the motor starting winding 67 into the circuit. Also connected in circuit in series with the starting winding of the motor and adapted to be energized simultaneously therewith is the unloading coil 54 previously 105 described, and a relay shunt coil 68.

110 A refrigerating unit constructed and equipped with an unloading device as described, and associated with a refrigerator in active use, operates as follows:

115 Assuming that the temperature in the refrigerator box is high, the master control switch associated therewith will act to close the circuit to the running winding 64 of the motor. Upon initial closure of the circuit a surge of current is effected through the line which is sufficient to energize the solenoid winding 65 of the switch 66 to close the circuit through the motor starting winding 67 and the winding of the unloading magnet 54.

120 Energization of the unloading magnet draws the armature arm 53 of the rocker shaft 46 toward the core 56 to effect partial rotation of the shaft and lifting of the pins 44 to unseat the suction valves 39. The motor, therefore, is free of 125 the compression load of the compressor, since the pistons, upon drawing refrigerant into the cylinders, return it through the open suction valves to the low compression chamber and no compression is effected. This condition is maintained in the compressor until the motor attains its normal working speed, or until the current consumption has dropped below the amount necessary to energize the solenoid switch winding 65. When this occurs, the armature lever arm 130 is released to permit the spring 61 to return the rock shaft to normal position and allow seating of the suction valves.

135 The suction valves are then free to function according to the movements of the pistons, which, on their suction strokes, draw refrigerant from the low pressure chamber into the ports 17, channels 18, past the suction valves and into the cylinders. At the end of the suction strokes, the ports 17 are uncovered to assure complete filling 140 of the cylinders with refrigerant, in order that the compressor can operate at maximum efficiency. On the beginning of the compression strokes, the ports 17 are, of course, closed by the piston, at which time the compression pressure closes the 145 150

suction valves aided by the spring 41. The entrapped refrigerant is then discharged past the valves 39 into the high pressure chamber 23.

The compressor continues to operate to develop the required pressure difference between the high and low pressure chambers, or until the master control switch has functioned to stop operation of the motor. Upon functioning of the master control switch the winding 65 is again temporarily energized by the current surge to effect operation of the unloading mechanism, as previously described.

It is apparent that while there is an initial surge of current incidental to closing of the motor circuit, this surge never rises above the safe capacity of the supply line fuses, since this surge functions to automatically relieve the motor of its compression load, whereupon the surge begins to drop to that normally required to operate the motor at its rated speed, which, of course, reduces the current flow below the value required to energize the switch solenoid, and it is at this time that the compression load is applied to the motor. The current value therefore cannot possibly rise above that required to energize the solenoid switch winding which is below the safe capacity of the line.

Attention is directed to the fact that with the unloading mechanism functioning as described, the compressor is not required to begin operation against pressure in the high pressure chamber, because as soon as the suction valves are raised the pressures above the piston are equal to the pressures of the low pressure chamber. Such conditions often occur due to momentary failure of the current at a time the compressor is operating so that a pressure is partly built up in the high pressure side. Then before the partially built-up pressure has time to equalize with the low pressure side, the current again comes on to start the motor.

Intermittent operation of the motor or even reduction of the motor speed, due to line or other conditions, will cause operation of the unloading mechanism because reduction of speed will effect a current surge sufficient to energize the switch solenoid 65.

What I claim and desire to secure by Letters Patent is:

50. 1. In a compressor, a cylinder housing having a low pressure chamber, a compression cylinder in the housing having a suction port communicating with said chamber, a valve normally closing said port, a piston operable in the cylinder, a motor operably connected with the piston, a circuit for supplying current to the motor, means in the housing adapted to engage said valve to retain the valve in open position, and an electro-magnet connectible in said circuit for actuating said valve-engaging means during excessive surges of current through the circuit.

55. 2. In a compressor, a housing having a low pressure chamber and a high pressure chamber, a cylinder in the housing, a piston operable in the cylinder for drawing gas from the low pressure chamber and discharging it into the high pressure chamber, valves controlling flow from the low pressure chamber to the cylinder and from the cylinder to the high pressure chamber, a rocker shaft pivotally mounted in the housing, a lever arm on the rocker shaft, a valve-engaging pin supported by the lever arm and adapted to engage the valve controlling flow from the low pressure chamber to the cylinder, a motor for actuating the piston, a circuit supplying current

to the motor, a secondary circuit, a solenoid switch in the first named circuit for energizing the secondary circuit upon surges of current through the first named circuit, a magnet in the secondary circuit, and means operable by the magnet for actuating the rocker shaft to retain said suction valve in non-functional position.

5. In a compressor, a cylinder housing having a low pressure chamber, a cylinder in the housing having a suction port communicating with said chamber, a valve closing said port, a piston operable in the cylinder, a motor operably connected with the piston, a circuit for supplying current to the motor, means in the housing adapted to engage said valve to retain the suction valve in open position, and an electro-magnet operably connectible in said circuit for actuating said valve-engaging means during initial starting of the motor to relieve the motor of the starting torque of the compression load of the compressor.

4. In a compressor, a housing having a low pressure chamber and a high pressure chamber, a cylinder in the housing, a piston operable in the cylinder for drawing gas from the low pressure chamber and discharging it into the high pressure chamber, valves controlling flow from the low pressure chamber to the cylinder and from the cylinder to the high pressure chamber, a motor for actuating the piston, a circuit supplying current to the motor, and means for rendering one of said suction valves ineffective including a secondary circuit, a solenoid switch in the first named circuit for rendering the second circuit effective upon surges of current through the first named circuit, an electro-magnet in the second named circuit, and means operable by the magnet for engaging said valve.

5. In combination with a compressor including low and high pressure chambers, a cylinder having a suction port communicating with the low pressure chamber and a discharge port communicating with the high pressure chamber, valves for said ports, a piston operable in the cylinder, a motor for operating the piston, a circuit for supplying current to the motor, and means operable in response to initial surge of current in the circuit for opening the suction valve and rendered inoperable in response to reduction in current flow to that required for operating the motor at its rated speed.

6. In combination with a compressor including low and high pressure chambers, a cylinder having a suction port communicating with the low pressure chamber and a discharge port communicating with the high pressure chamber, valves for said ports, a piston operable in the cylinder, a motor for operating the piston, a circuit for supplying current to the motor, and an electro-magnet connected for energization by initial surge of current in the circuit and for de-energization in response to reduction of flow of current in the circuit to that required for operating the motor at running speed, the magnet having an armature operable to open the inlet valve when the magnet is energized.

7. In combination with a compressor including low and high pressure chambers, a cylinder having a discharge port communicating with the high pressure chamber and an inlet port communicating with the low pressure chamber, valves for said ports, a piston in the cylinder, a motor for operating the piston, a primary circuit for supplying current to the motor including a running winding, a starting winding having a nor-

normally open secondary circuit, an electro-magnet in circuit with the starting winding, means operable in response to initial surge of current in the primary circuit for closing the secondary circuit and to reduction in flow of current in the primary circuit to that required for operating the motor at running speed for opening the secondary circuit, and means operable by the magnet for opening the inlet valve and retaining the said valve open during the starting phase.

8. In combination with a compressor including low and high pressure chambers, a cylinder having a discharge port communicating with the high pressure chamber and an inlet port communicating with the low pressure chamber, valves for said ports, a piston in the cylinder, a motor for operating the piston, a primary circuit for

supplying current to the motor including a running winding, a starting winding having a normally open secondary circuit, an electro-magnet in circuit with the starting winding, means operable in response to initial surge of current in the primary circuit for closing the secondary circuit and to reduction in flow of current in the primary circuit to that required for operating the motor at running speed for opening the secondary circuit, means operable by the magnet for opening the inlet valve and retaining the said valve open during the starting phase, and yielding means for returning said valve actuating means to permit the valve to close when the magnet is de-energized.
